UNITED STATES PATENT OFFICE

127,952

DESIGN FOR A CABINET FOR SOUND REPRODUCING APPARATUS

David C. Rockola, Chicago, Ill., assignor to Rock-Ola Manufacturing Corporation, Chicago, Ill., a corporation of Delaware

Application February 5, 1941, Serial No. 98,755

Term of patent 3½ years

To all whom it may concern:

Be it known that I, David C. Rockola, a citizen of the United States, residing at Chicago, in the county of Cook and State of Illinois, have invented a new, original, and ornamental Design for a Cabinet for Sound Reproducing Apparatus, of which the following is a specification, reference being had to the accompanying drawing, forming a part thereof.

Fig. 1 is a perspective view of a cabinet for sound reproducing apparatus showing my new design, the opposite side walls of the cabinet being similar and the rear wall being plain; and

Fig. 2 is a top plan view of the casing.

I claim:

The ornamental design for a cabinet for sound reproducing apparatus, substantially as shown and described.

DAVID C. ROCKOLA.
